(57) **CLAIM**

The ornamental design for a biometric sensor, as shown and described.

DESCRIPTION

FIG. 1 is a front, top, right side perspective view of a biometric sensor showing our new design;

FIG. 2 is a rear, bottom, left side perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a perspective view of the biometric sensor in an exemplary environment therefor;

FIG. 10 is a right side view thereof;

FIG. 11 is a left side view thereof;

FIG. 12 is a front view thereof;

FIG. 13 is a rear view thereof;

FIG. 14 is a top view thereof; and,

FIG. 15 is a bottom view thereof.

The broken lines in the drawings illustrate environmental structure for the biometric sensor in the form of a mobile telephone that form no part of the claimed design.

1 Claim, 9 Drawing Sheets
